UNITED STATES PATENT OFFICE.

WILLIAM J. WOOLLEY, OF ANDERSON, INDIANA.

TILE-MACHINE.

SPECIFICATION forming part of Letters Patent No. 361,037, dated April 12, 1887.

Application filed January 15, 1887. Serial No. 224,466. (No model.)

To all whom it may concern:

Be it known that I, WILLIAM J. WOOLLEY, a citizen of the United States, residing at Anderson, in the county of Madison, State of Indiana, have invented certain new and useful Improvements in Tile-Machines, of which the following is a specification, reference being had therein to the accompanying drawings. This invention has relation to tile-machines which are adapted for the production of either large or small sized tiles by changing the relative positions of the tempering and forcing cylinders with relation to the table of the machine; and among the objects of the invention are the provision of means for changing the said relative positions of the cylinders, and to provide a fixed hopper and a cylinder so constructed to operate in connection therewith that the former may perform its function in either position of the cylinder, and this without the necessity of removing and replacing certain parts.

Another object of the invention is to provide an adjustable cut-off mechanism which shall be automatically controlled to determine the length of the product to be severed.

Other objects and advantages of the invention will appear in the following description, and the novel features thereof will be particularly pointed out in the claims.

Referring to the drawings, Figure 1 is a side elevation of a tile-machine constructed in accordance with my invention. Fig. 2 is a vertical section taken on the line $x-x$ of Fig. 1. Fig. 3 is a modification, and Fig. 4 is a detail in perspective of the cut-off mechanism.

Like letters of reference indicate like parts in all the figures of the drawings.

A A represent the legs or standards of a suitable frame-work for supporting the machine, and this may or may not, as desired, be arranged upon a foundation, A', of masonry or frame-work. Each of the standards A comprises legs proper and a segmental cross-bar, A², with any number or form of suitable tie-bars, A³. The cross-bars A² are segmental, in order to form a suitable bearing for the tempering-cylinder B of the machine.

Attached to or formed as a part of the tempering-cylinder, as may be desired, is a forcing-cylinder, B', to which are secured the dies, hereinafter described.

Within the tempering-cylinder there is

mounted a shaft, B², from which project blades B³, and at the inner end is mounted a feed-screw, B⁴, these parts being of the usual construction.

In the forcing-cylinder B', which, as before stated, may be formed in one piece with the tempering-cylinder, there is arranged a shaft, B⁵, (see dotted lines, Fig. 1,) having mounted thereon a feed-screw, B⁶, the shaft being hollow for the purpose of the passage therethrough of the core-shaft B¹⁰, so that the core B¹¹ is supported in proper relation to the die C, secured to the cylinder.

To the hollow shaft B⁵ there is secured for operation a miter-gear, B⁷, which meshes with a companion gear, B⁸, secured to a shaft, B⁹, mounted in bearings D D', the former supported by a bracket, D², formed on or affixed to the head B⁹ of the forcing-cylinder. The upper end of the core-shaft B¹⁰ is supported on a bracket, B¹², mounted or cast on the head of the cylinder. This bracket is provided with a bearing, B¹³, for the hollow shaft, and with a cap, B¹⁴, made in the form of an oil-cup, the top of the cap being perforated, as at B¹⁵, for the introduction of oil, and its bottom being perforated, as at B¹⁶, for the passage of oil therefrom down into contact with the hollow shaft. The bearing D' for the shaft B⁹ is formed as a part of or it may be secured to the head B¹⁷ of the tempering-cylinder. A pinion, E, is mounted on the shaft B⁹ and meshes with a gear, E', mounted on the shaft B⁵. There is also mounted on the shaft B⁹ a gear, E², meshing with the pinion E³, mounted on the shaft B⁵, and upon the latter is mounted the belt-pulley E'. The cylinder B is provided with an opening, F, (see dotted lines, Fig. 1,) which is covered by a curved strap-like plate, F', each end of which is connected with the framework, so as to be supported independently of the cylinder, and so as to be held in snug contact therewith, in order to always cover the opening without regard to the change in the position of the cylinder, hereinafter described.

Upon the plate there is formed or attached a hopper, G, which communicates with the opening in the cylinder B. In this instance each end of the plate F' is provided with a lug, F², through which a bolt, F³, from any fixed part of the machine passes, a nut, F⁴, serving with the bolt to secure the end of the plate rigidly to the frame.

As illustrated in Fig. 1, a bracket, F' , is secured to one of the standards A and projects beneath the end of the plate F , and through this bracket the bolt F' passes, so that said plate may be drawn either firmly in contact with the bracket, or, for the purpose of taking up wear and causing the plate to snugly fit the cylinder over which it passes, a space may be provided between the end of the plate and the bracket.

In Fig. 2 I have illustrated the cylinders B' turned so as to present the die C at one side in order to deliver from the machine small tiles in a horizontal direction, the position indicated in Fig. 1 being such as to deliver large tiles upon a table, hereinafter described, and in a vertical direction. The means which I have shown in this instance for turning the cylinder involve the principle of a screw, in that there is attached, at a suitable point on the horizontal portion of the cylinder, brackets H, in which is mounted a swiveled or pivoted nut, H', through which a threaded shaft, H², passes. Upon one of the standards of the machine is secured a bracket, H³, in which is pivoted an eyebolt, H⁴, for the reception and bearing of the shaft H². A crank, H⁵, is fixed to the shaft, whereby it may be turned. Taking the cylinder in the position illustrated in Fig. 1, it may be caused to assume the position shown in Fig. 2 by turning the crank H⁵ and causing the nut H' to travel toward an end of the shaft H², and the shaft, bracket, and nut will assume the position indicated by dotted lines in Fig. 2. A reversal of the rotation of the shaft will return the cylinder to a position shown in Fig. 1.

Now the opening F in the cylinder is sufficiently extended to provide an unobstructed passage from the hopper into the cylinder in whichever of the two described positions it may be arranged. In turning the cylinder from one position to the other, it may be advisable to loosen the nuts F', whereby the friction of the band upon the cylinder is reduced.

Instead of employing the swiveled nut and the threaded shaft mounted in a swiveled eyebolt, it is apparent that I may employ a curved rack, H', (see Fig. 3,) and a worm, H², mounted upon a shaft having fixed bearing-brackets H⁴, and a crank, H⁵, when the same movement of the cylinder will be reproduced as with the devices previously described. In these devices or any equivalents thereof it will be observed that there is no necessity or requirement of raising the cylinder from the standards in order to change its position.

Below the cylinder there are arranged uprights I, in which is a table-carrying frame, I', provided with a rack, or its equivalent, meshing with a pinion mounted on the shaft I², provided with a hand-wheel, I³, whereby the table-supporting frame may be elevated and depressed, as desired. From the frame there extends a bracket, I⁴, in which is pivoted a table, I⁵.

J represents the cut-off shaft, which is mounted in brackets J', projecting from the uprights I. To the table-frame is suitably and adjustably secured, by means of a thumb-nut, K', a sleeve, K, carrying a finger, K², projecting toward the cut-off shaft. The latter is provided with a quadrant, L, which, by means of a set-screw, L', is adjustably secured to the shaft.

M represents the cut-off, which comprises in its make-up a curved frame, M', removably secured in a collar, M², by means of a set-screw, M³. The collar M² is adjustably secured to the cut-off shaft J by a set-screw, M⁴. A wire, M⁵, is stretched from end to end of the frame, and may be secured by set-screws M⁶. The object of making the cut-off frame removably attached to the collar is to permit of the substitution of frames with a curvature, whereby they are adapted to large or to small tiles, the larger frame being unwieldy and otherwise unsatisfactory in cutting small tiles.

A cord, N, and weight N' are arranged above the machine on suitable pulleys, N², and connected with the cut-off shaft J, whereby the latter and its accessories have a constant tendency to rise, while the finger K², which by any suitable means is adjustably secured to the table-frame, is brought into contact with the quadrant L as a tile is passing from the die, with its lower end resting upon the table or a board set thereon, as is customary. In this manner a downward movement is given to the cut-off M, which is synchronous with that of the tile, so that as the cut is being made the cut-off advances with the tile, and the result is a severance of the product squarely—that is, at a right angle to its length. Now, by means of the adjustable attachment of the cut-off to the shaft J, longer or shorter sections of the product may be made.

The adjustment of the cut-off proper is limited to a position on the rod between the bearings J' thereof; hence I attach the quadrant below the bearings and get an additional means of adjustment not dependent upon the distance apart of the bearings; but the quadrant is limited in adjustment to the length of the shaft projecting below the lower bearing thereof, so that a special advantage is inherent in rendering the finger itself adjustable. This adjustability of the finger is independent, also, of the position of the bearings, as it may be extended up the frame to a point above the lower bearing. In the latter case it is apparent that the finger will fall with the table coming in contact with the quadrant at the lower bearing, and carrying it and the cut-off shaft down along with the table and the product thereon.

This being the construction, the general operation of the machine may be restated as follows: Clay, being supplied to the cylinder through the hopper G and opening F, is tempered, worked, and pressed by the blade-shaft B³ and screw B⁴, and when coming in contact

with the hollow shaft B^6 and its screw is forced through the die in the form desired—that is, either as a large or small tile, the former, on account of their size, being delivered vertically upon the table, as described, and cut to proper size by the cut-off, which has been previously adjusted as desired.

Now, in order to produce small tiles, a proper die is substituted for the die C, (shown in Fig. 1,) the strap or plate F' is loosened or not, as necessary, and the cylinder is turned so as to present its die at one or the other side, as desired.

It is apparent that other devices than those herein shown and described for supporting the plate in proper relation to the opening in the cylinder may be employed, and I therefore do not limit my invention in this regard to the specific devices shown.

The object of the quadrant L is to retain the control of the finger throughout the sweep of the cut-off.

By referring to Fig. 1 it will be seen that a portion of the cylinder B is broken away to expose the inner end or bearing of the tempering-shaft B^2 , which, as before described, is provided with blades for tempering the clay, and may or may not, as desired, be provided with an auger or screw at its extreme end for more positively feeding the tempered clay into the forcing-cylinder than would the blades by themselves. This bearing embodies a novel construction, and has for its object the preservation of the shaft from the cutting action of the clay, which, as is well known, soon destroys the revolving part by reducing it so as to render the shaft unfitted for use. By my improvement I preserve the shaft and substitute a removable part to take the wear, in order that it may be replaced by another like it and at a much less expense than that involved in replacing the entire shaft. The shaft B^2 may or may not be reduced at the point where it is supported by the bearing. In this case, however, I have shown the shaft reduced and have fitted thereto a collar or sleeve, P, which is preferably made of steel, or it may be of any other desired material. This collar is fixed upon the shaft either by a driving fit or by a key and spline, P', so as to revolve with the shaft. The bearing proper, P^2 , fits the collar or sleeve P, and is supported within the cylinder by rods or standards P³, fastened by exterior nuts, P⁴. Now, it is apparent that after the contact-surface of the collar or sleeve is worn so as to become loose or unfitted to the bearing P^2 , it may be removed and another collar substituted therefor, thus saving the expense of a new shaft. Access is secured to this part of the cylinder either by means of a plate, P⁵, secured to the compressing-cylinder and covering an opening therein, or, if desirable, the opening F may serve the same purpose as well as to give access for the purpose of removing and replacing blades on the shaft.

It is also apparent that the collar need not

be restricted in its length to agree with that of the bearing. It is also evident that this construction of bearing is applicable to all mechanisms intended for tempering or working clay.

Having described my invention and its operation, what I claim is—

1. In combination with the cylinder of a tile-machine, standards for supporting the same, and mechanism connected with the cylinder and with the standards for turning the cylinder to present its die in different positions, substantially as specified.

2. The combination, with the cylinder of a tile-machine, of standards having a curved bearing for the cylinder, and a screw-shaft connected with the standards and with the cylinder for turning the same, substantially as specified.

3. The combination, with the cylinder of a tile-machine, and with its standards, of a swiveled nut connected with the machine, and a threaded shaft operating in the nut and in a swiveled eyebolt or bracket mounted on the standards, substantially as specified.

4. In a tile-machine, a cylinder provided with an opening, in combination with a plate arranged over the opening and supporting a hopper, substantially as specified.

5. In a tile-machine, the combination, with the cylinder provided with an opening, of a plate arranged over the opening and a hopper, substantially as specified.

6. In a tile-machine, the combination, with its cylinder having an opening, of a plate adjustably connected with the frame-work and embracing the cylinder over the opening, and a hopper communicating with said opening, substantially as specified.

7. In a tile-machine, the combination of the core, a pipe encircling the same, and a cap made in the form of an oil-cup, substantially as specified.

8. The cut-off M, comprising a collar, M¹, a removable frame, M², and a wire, M³, substantially as specified.

9. A cut-off shaft provided with an adjustably and rigidly mounted quadrant, substantially as and for the purpose specified.

10. A cut-off shaft provided with an adjustable cut-off and an adjustable quadrant, in combination with a dog connected with the table to partake of its movement and projecting into the path of the quadrant, substantially as specified.

11. The combination, with the cut-off shaft J, of the adjustable cut-off, the adjustable quadrant, and the adjustable dog, substantially as specified.

In testimony whereof I affix my signature in presence of two witnesses.

WILLIAM J. WOOLLEY.
